(57) **CLAIM**

The ornamental design for a chair, as shown and described.

DESCRIPTION

FIG. 1 is a top perspective view of a chair showing my new design;

FIG. 2 is a bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is an enlarged detailed view of the encircled area 9 in FIG. 2.

The dot-dash broken lines shown in FIG. 2 and FIG. 9 illustrate the border of the enlarged detailed view and form no part of the claimed design.

1 Claim, 9 Drawing Sheets
